CASHBOX

William H. Whitecomb, Portland, Oreg.

Application September 2, 1947, Serial No. 771,589

10 Claims. (Cl. 206—83)

1

My present invention relates to a petty cash box of utility in financial institutions, stores, or other establishments wherein small coins are handled. The device is of use to clerks in making change, to professional men in keeping petty cash, to bank tellers in handling withdrawals, and in many other similar situations.

An object of the present invention is to provide a durable box for replacing the canvas bags commonly used for small coins, which bags wear out very quickly.

A further object of the present invention is to provide a cash box adapted to hold a definite amount of small change in certain proportions of the various denominations. This will promote the availability of proper change in the hands of each clerk, since it will be easier for a clerk to maintain a certain amount of change on hand than to bother a cashier from time to time.

A further object of the present invention is to provide a cash box for holding certain numbers of coins of different denominations, which is so designed that it is impossible to have more than a desired number of each coin, and it is readily ascertainable if less than a desired number of each coin is present.

The foregoing and other objects and advantages of the present invention will be more readily apparent from inspection of the accompanying drawings taken in connection with the following specification wherein like numerals refer to like parts throughout, while the features of novelty will be more particularly pointed out in the appended claims.

In the drawings, Fig. 1 is a perspective view of the invention showing the cash box partially opened;

Fig. 2 is a plan view of the box when fully opened;

Fig. 3 is a longitudinal section taken substantially along line 3—3 of Fig. 2 but showing the complementary halves of the coin holding sections in closed relation;

Fig. 4 is an end view of the cash box in fully closed position;

Fig. 5 is a partial sectional view taken substantially along line 5—5 of Fig. 1; and

Fig. 6 is a sectional view taken substantially along line 6—6 of Fig. 5.

The invention comprises a lower tray 10, an upper tray 11, and a cover member 12, the three members being hinged together along an edge at 13 and 14. The tray 10 is provided with a plurality of substantially semicylindrical grooves 15, and the complementary tray 11 is provided

2

with a plurality of matching grooves 16, the grooves 15 and 16 when placed in the superimposed relationship forming a substantially cylindrical space adapted to contain coins of a certain size such as pennies. Tray 10 is provided with a similar groove 17 complementary to a groove 18 in tray 11 adapted to provide space for a row of nickels. Similar pairs of grooves are provided such as 19 and 20 for dimes, 21 and 22 for quarters, and 23 and 24 for half-dollar coins. Each of the grooves is broken into individual steps such as the steps 25 indicated in groove 15, each step being adapted to hold a certain number of coins of the denomination adapted to fit into the groove, as illustrated in Fig. 2. The length of each step is accurately determined by taking the over-all length of several hundred coins of that denomination and dividing by a factor designed to give a result equal to the length of the desired number of coins for each step. Accordingly, only that number of coins may be rested on each step, hence the owner knows at a glance the total value of coins present in the box. The steps 25 are so designed that their axes are substantially parallel and at an inclination to the surface of the tray so that the bottom of each groove presents a succession of alternate anticlines and synclines whereby the rows of coins are broken up into series of offset denominational groups.

The bottom of each tray is substantially open; and at least one end wall of the lower tray 10 is provided with an edge notch 28 through which the fingers of one hand may be inserted to facilitate lifting the filled box from a table. The bottom, which becomes the top when the tray is closed, of tray 11 is covered by a thin sheet of metal 26 which is preferably provided with an offset tongue 27 struck from the metal so as to provide a clip wherein paper money may be retained. The edge dimensions of tray 11 are less than those of tray 10 in order to permit the walls of lid 12 to rest flush with the walls of tray 10.

The lid member 12 is provided with a retainer 30 projecting therefrom through which there is an opening 31, the retainer being in position to slip into a slot 32 through the upper surface of the tray 10. In order to permit closure of the lid 12, the side walls of the tray 11 are sloped inwardly to clear the rounded edges of the tray 11; and one wall of the tray 11 is recessed at 33 to provide a groove for reception and passage of the retainer 30. A boss 35 is provided on the tray 10 in which is slidably seated a bolt 36

adapted to extend through the opening 31 in the retainer 30 so as to latch the box in closed position. A side wall of the boss 35 is recessed at 37 to provide clearance for the passage of a bolt operating knob 38 which also acts to retain the bolt within the boss against the force of a spring 39 tending to force it into latching position. The knob 38 may be engaged by inserting fingers beneath the tray 10 and compressing the spring 39, whereupon the box may be opened. The front end of the bolt 36 may be provided with a rounded or sloping surface 40 so that the lid may be snapped shut without requiring withdrawal of the bolt by manipulating knob 38. Assembly of the bolt in the tray 10 is accomplished by slipping the bolt longitudinally through an opening 41 and then assembling the knob 38 to the bolt as by means of screw threads. The recess 37 is curved so as to force the bolt 36 into proper position, and also provides means whereby withdrawal of the bolt is effected by pulling knob 38 down.

It is to be noted that each groove in the lower tray 10 is provided with an end wall 45 extending substantially normal to the axes of the inclined steps so that coins will rest in substantially cylindrically positioned groups. The opposite end wall 46 of each groove is disposed at a divergent angle so as to permit insertion and removal of the last group of coins. The end walls of the grooves in the tray 11 are disposed in reversed relation so that the end wall 47 which overlies the end wall 46 is normal to the axes of the steps and the end wall 48 which overlies the end wall 45 is disposed divergently. This relationship of the end wall 47 assures the compacting of the row of coins when the box is closed so that the coins in a filled row will be snugly embraced and prevented from rattling. Also if, by any chance, more than the desired number of coins should be placed in a row, one of the steps, or the end wall 47, will strike a coin and prevent the lid from being fully closed, thus providing a quick check against oversupply of coins of a certain denomination. The divergent position of the end wall 48 permits the upper tray 11 to be closed since it may thus clear the first coin in a row.

The grooves 23 and 24 for the reception of half-dollar pieces are single steps but retain the same characteristics inasmuch as the end walls 50 and 53 are normal to the axes of the grooves, the end walls 52 are vertical, but nevertheless divergent from the end walls 50 and 53 and the end walls 51 are inclined, thus providing the same features as with respect to the grooves having a plurality of steps.

Having illustrated and described the preferred embodiment of my invention, it will be apparent to those skilled in the art that modifications in detail and arrangement thereof are permissible. All such modifications as come within the true spirit and scope of the appended claims are considered to be a part of my invention.

I claim:

1. A coin box comprising a lower tray, and an upper tray hingedly attached to said lower tray along an edge thereof, said lower tray having a plurality of substantially semi-cylindrical grooves therein normal to said edge adapted to accommodate rows of coins of various denominations, the bottoms of at least several of said grooves presenting series of alternate anticlines and synclines whereby the rows of coins therein are broken up into series of offset denominational

groups, and said upper tray having similar grooves provided with equal and opposed anticlines and synclines to complement the grooves of said lower tray.

2. A coin box comprising a lower tray, and an upper tray hingedly attached to said lower tray along an edge thereof, said lower tray having a plurality of substantially semi-cylindrical grooves therein normal to said edge adapted to accommodate rows of coins of various denominations, the bottoms of at least one of said grooves presenting a series of alternate anticlines and synclines whereby the row of coins therein is broken up into a series of offset denominational groups, and said upper tray having grooves provided with equal and opposed anticlines and synclines to complement the grooves of said lower tray.

3. A coin box comprising a lower tray, an upper tray hingedly attached to said lower tray along an edge thereof, said lower tray having a plurality of substantially semi-cylindrical grooves therein normal to said edge adapted to accommodate rows of coins of various denominations, the bottoms of a plurality of said grooves presenting series of alternate anticlines and synclines whereby the rows of coins therein are broken up into series of offset denominational groups, and said upper tray having similar grooves provided with equal and opposed anticlines and synclines to complement the grooves of said lower tray, and a lid hingedly attached to said lower tray along said edge.

4. A coin box comprising a lower tray, an upper tray hingedly attached to said lower tray along an edge thereof, said lower tray having a plurality of substantially semi-cylindrical grooves therein normal to said edge adapted to accommodate rows of coins of various denominations, the bottoms of the majority of said grooves presenting series of alternate anticlines and synclines whereby the rows of coins therein are broken up into series of offset denominational groups, and said upper tray having similar grooves provided with equal and opposed anticlines and synclines to complement the grooves of said lower tray.

5. A coin box comprising a first tray having a plurality of upwardly facing, substantially parallel grooves therein, each of certain of said grooves being formed to present a succession of semi-cylindrical steps whose axes are substantially parallel and inclined at an acute angle with respect to the plane of the tray, one end wall of each groove being substantially normal to said axes, and the opposing end wall being disposed in a plane forming a divergent angle with the plane of said one end wall, and an upper tray hingedly connected to an edge of said lower tray normal to said grooves and having a plurality of complementary grooves formed therein, each of certain of said complementary grooves being shaped to form, together with the grooves in said lower tray, a plurality of substantially cylindrical spaces each of a size snugly to embrace a group of coins.

6. A coin box comprising a first tray having a plurality of upwardly facing, substantially parallel grooves therein, at least one of said grooves being formed to present a succession of semi-cylindrical steps whose axes are substantially parallel and inclined at an acute angle with respect to the plane of the tray, one end wall of said groove being substantially normal to said axes, and the opposing end wall being disposed in a plane forming a divergent angle with the plane

of said one end wall, and an upper tray hingedly connected to an edge of said lower tray normal to said grooves and having a plurality of complementary grooves formed therein, at least one of said complementary grooves being shaped to form, together with said groove in said lower tray, a plurality of substantially cylindrical spaces each of a size snugly to embrace a group of coins.

7. A coin box comprising a first tray having a plurality of upwardly facing, substantially parallel grooves therein, each of certain of said grooves being formed to present a succession of semi-cylindrical steps whose axes are substantially parallel and inclined at an acute angle with respect to the plane of the tray, one end wall of each groove being substantially normal to said axes, and the opposing end wall being disposed in a plane forming a divergent angle with the plane of said one end wall, and an upper tray hingedly connected to an edge of said lower tray normal to said grooves and having a plurality of complementary grooves formed therein, each of certain of said complementary grooves being shaped to form, together with the grooves in said lower tray, a plurality of substantially cylindrical spaces each of a size snugly to embrace a group of coins, the end walls of each of said complementary grooves being disposed similarly to the end walls of the grooves in said lower tray but in reversed relation thereto when the trays are in closed relation to each other.

8. A coin box comprising a first tray having a plurality of upwardly facing, substantially parallel grooves therein, at least one of said grooves being formed to present a succession of semi-cylindrical steps whose axes are substantially parallel and inclined at an acute angle with respect to the plane of the tray, one end wall of said groove being substantially normal to said axes; and the opposing end wall being disposed in a plane forming a divergent angle with the plane of said one end wall, and an upper tray hingedly connected to an edge of said lower tray normal to said grooves and having a plurality of complementary grooves formed therein, at least one of said complementary grooves being shaped to form, together with said groove in said lower tray, a plurality of substantially cylindrical spaces each of a size snugly to embrace a group of coins, the end walls of said complementary groove being disposed similarly to the end walls of said groove in said lower tray but in reversed relation thereto when the trays are in closed relation to each other.

9. A coin box comprising a first tray having a plurality of upwardly facing, substantially parallel grooves therein, each of certain of said grooves being formed to present a succession of semi-cylindrical steps whose axes are substantially parallel and inclined at an acute angle with respect to the plane of the tray, one end wall of each groove being substantially normal to said axes, and the opposing end wall being disposed in a plane forming a divergent angle with the plane of said one end wall, and an up-

per tray hingedly connected to an edge of said lower tray normal to said grooves and having a plurality of complementary grooves formed therein, each of certain of said complementary grooves being shaped to form, together with the grooves in said lower tray, a plurality of substantially cylindrical spaces each of a size snugly to embrace a group of coins, each of said complementary grooves in said upper tray having its end wall adapted to be juxtaposed to the said one end wall of the groove in the lower tray disposed at an angle divergent from a plane normal to the axes of said grooves, and its end wall adapted to be juxtaposed to the opposite end wall of the groove in said lower tray disposed in a plane normal to the axes of said grooves.

10. A coin box comprising a first tray having a plurality of upwardly facing, substantially parallel grooves therein, each of certain of said grooves being formed to present a succession of semi-cylindrical steps whose axes are substantially parallel and inclined at an acute angle with respect to the plane of the tray, one end wall of each groove being substantially normal to said axes, and the opposing end wall being disposed in a plane forming a divergent angle with the plane of said one end wall, an upper tray hingedly connected to an edge of said lower tray normal to said grooves and having a plurality of complementary grooves formed therein, each of certain of said complementary grooves being shaped to form, together with the grooves in said lower tray, a plurality of substantially cylindrical spaces each of a size snugly to embrace a group of coins, each of said complementary grooves in said upper tray having its end wall adapted to be juxtaposed to the said one end wall of the groove in the lower tray disposed at an angle divergent from a plane normal to the axes of said grooves, and its end wall adapted to be juxtaposed to the opposite end wall of the groove in said lower tray disposed in a plane normal to the axes of said grooves, a lid hingedly attached to said edge and adapted to enclose said upper tray, and means to latch said lid to said lower tray.
